FRONT END FOR EXCAVATING MACHINES

Trevor O. Davidson, Milwaukee, Wis., assignor to
 Bucyrus-Erie Company, South Milwaukee, Wis.,
 a corporation of Delaware

Application November 17, 1947, Serial No. 786,446

3 Claims. (Cl. 214—135)

1

My invention relates to new and useful improvements in excavators and more particularly to excavators of the type having a boom and an outward digging dipper mounted on the end of a handle, which handle is reciprocable with respect to a shipper shaft on the boom, the dipper being movable in approximately a circle about this shaft.

The usual construction of the digging mechanism of power shovels, dredges and the like, consists of an inclined boom, the lower end of which rests on the main structure of the machine, the upper end being supported by guys which are generally anchored to a mast, which in turn is anchored to the rear end or part of the structure carrying the hoisting machinery. At approximately the middle of the boom a saddle block is hinged, through which passes the dipper handle under control of the shipper shaft on which the saddle block is pivoted. The actual digging element, the dipper, is attached to the outer end of the dipper handle. There is also attached to the dipper a rope, or ropes, which pass over a sheave or sheaves at the outer end of the boom and thence to the hoisting machinery. The boom is usually inclined about 45° to the horizontal. Means are provided for causing the dipper handle to move in and out through the saddle block.

In the past, two modifications of the above-described conventional construction have been employed in order to provide greater digging force from a given rope pull at lower positions of the dipper and/or to reduce torsional stress produced in the boom by the dipper handle due to swinging inertia of the dipper and side-thrust of the bank:

(1) The dipper handle has been slidably mounted on a fixed boom which terminates at the shipper shaft, and the dipper hoist line has been passed over a sheave mounted at the end of a short movable mast pivoted at the end of the boom. See U. S. Patent No. 2,015,629, issued September 24, 1935, to Samuel Lippincott Griswold Knox.

(2) The dipper handle has been hinged or jointed at its rear end to a movable boom pivoted on the main frame of the machine and terminating at the hinge or joint, and the dipper hoist line has passed over a sheave mounted at the end of a long fixed mast pivoted on the main frame. See U. S. Patents Nos. 2,139,254 and 2,139,255 issued December 6, 1938, to Kenneth R. Bixby.

There are, however, a number of disadvantages with each of these modifications.

On the one hand, in the Knox design, pivoting

2

the mast at the end of the boom makes for high tension in the mast hoist line and high compression stresses in the mast when it is lowered to obtain high digging forces in a low pit, and accordingly the sheave supports, the mast, the boom, and the boom braces must be heavily built. Furthermore, substantial torsional stresses are still imparted by the dipper stick to the boom through the saddle block and shipper shaft, again making it necessary to have a heavy boom and boom braces.

On the other hand, in the Bixby design, which has a fixed mast and a movable boom with dipper handle jointed on the boom, the reach of the dipper is shortened in low digging positions because the dipper stick must be drawn in with the boom to obtain the better digging component, and the dumping range is limited to points far out in front of the machine. Furthermore crowding movement requires more work, since at each pass of the dipper, not only the dipper handle, but also the boom and actuating arm must be moved. Furthermore, since the rear end of the Bixby dipper handle is fixed to the end of its supporting boom, the boom must be drawn in to a point substantially above the mast when digging low and/or close in to the mast, and accordingly the arc in which the dipper handle can swing sideways inside the mast is seriously restricted by the legs of the mast. Furthermore, since the Bixby dipper handle swings sideways about an axis perpendicular to the dipper handle, the dipper is free, when the dipper is raised to dumping position, to swing sideways in a wide arc whose radius is the full length of the dipper handle and accordingly in that position there is danger of interference between the dipper handle and the converging legs of the mast.

Accordingly it is the principal object of my invention to improve over the Knox and Bixby front-end constructions in various ways, including:

(1) Provision of a mounting for the boom and dipper handle in which torsional stresses in the boom due to swinging inertia and side thrust are eliminated without twisting of the dipper handle crowd drive.

(2) Provision of a swivel mounting for the dipper handle such that, as the dipper is raised to dumping position, the side swing of the dipper handle is automatically decreased, thereby preventing interference between the dipper handle and the upwardly converging legs of the mast.

(3) Provision of a front end construction in which dipper reach and dumping range is un-

3

affected by increase of the digging component in low positions of the dipper.

(4) Provision of a front end construction in which side swing of the dipper handle in low digging positions of the dipper will not be limited appreciably by the legs of the mast.

(5) Provision of a variable support for the dipper-hoist line sheave, said support being movable to provide greater digging force in low positions of the dipper, being mounted independently of the boom, and being so oriented that compression stresses in the sheave support are reduced.

(6) Provision of a front end construction having the advantages without the above-mentioned disadvantages of previous front-end designs.

In addition to my principal objects, above stated, I have worked out a number of novel and useful details, which will be readily evident as the description progresses.

My invention consists in the novel parts, and in the combination and arrangements thereof, which are defined in the appended claims, and of which two embodiments are exemplified in the accompanying drawings, which are hereinafter particularly described and explained.

Throughout the description, the same reference number is applied to the same member or to similar members.

Figure 1 is a plan view of one embodiment of my invention, in which the main supporting structure is shown conventionalized.

Figure 2 is a side elevation, of the same embodiment, taken along the line 2—2 of Figure 1.

Figure 3 is an enlarged interior side elevation, partly in section, of the short boom, and the crowd machinery, of the same embodiment, taken along the line 3—3 of Figure 1.

Figure 4 is a side elevation, similar to Figure 2, of a second embodiment of my invention.

Referring to Figures 1 to 3, it will be seen that 11 is the main frame of an excavator, revolvable on a propelling base 10. 12 is a boom swivelly mounted at its foot on the base, and inclined upwardly therefrom. The main frame 11 also carries structure 13, which may be (as shown) in the form of a conventional A-frame, or may take the form of a mast or any other conventional form. 14 is a strut extending from the top of the A-frame 13 to the outer end of the boom 12, and connected thereto by collar 15 which permits the boom to swivel about its axis within said collar. 16 is a dipper handle, carrying at its outer end a dipper 17. 18 is a shipper-shaft, located on the boom adjacent the juncture of strut 14 and boom 12, and pivotally supporting saddle block 19 within which reciprocation of the dipper handle 16 is effected by two ropes 20 and 21 passing around sheaves 22 on the shipper shaft, and anchored respectively to the front and rear ends of the dipper handle 16. Ropes 20 and 21 pass from the dipper handle 16 around sheaves 22 thence to drum 23 at the foot of the boom 12, to which drum they are eventually dead-ended. Gear 24 on drum 23 is actuated through pinion 25a by gear 25 which is in turn driven by conventional motor 26 (shown schematically), these being supported preferably on the boom, and preferably adjacent the foot of the boom. Mast 27, supported at its foot on main frame 11, preferably on spread pivots 28 at the front of the main frame adjacent the swivel support of the boom, extends beyond the outer end of the boom and supports dipper hoist-line sheaves 29. Tension member 30 between A-frame 13 and the outer end of mast 27 supports the mast at a fixed inclination. Dip-

4

per hoist lines 31 extend from the dipper 17 over sheaves 29 to a conventional winch 32 mounted on the main frame 11.

It will be seen that this construction results in reduced stresses in the boom, which can accordingly be built lighter, thereby reducing swinging moment and increasing efficiency. Compression stresses in the boom 12 are reduced, since only the dipper handle 16 is supported thereon, the dipper hoist line 31 being supported independently by mast 27. Torsion stresses in the boom 12, due to swinging inertia of the dipper and side thrust of the bank, are eliminated by having the boom swivelly mounted on the main frame 11. Since the drum 23 which controls the crowd ropes 20 and 21 is mounted on the boom and swivels with it, any twisting of crowd ropes 20 and 21 (or other forms of crowd drive) due to side motion of the dipper handle is avoided. Furthermore, since the dipper handle is not fixed but is longitudinally slideable with respect to the boom, it is possible to dig close to the machine when the boom is above or nearly aligned with the mast so that side swing of the dipper handle is practically unrestricted by the legs of the mast. And lastly, due to the fact that the dipper handle swings sideways about the axis of the boom (instead of an axis perpendicular to the dipper handle), we see that, as the dipper handle is raised to come more nearly into line with the boom, side swing of the dipper handle is more and more restricted until it becomes a mere tilting motion of the dipper about the boom axis; hence as the dipper handle is raised between the upwardly converging legs of the mast, interference between the dipper handle and the mast is automatically prevented.

Turning now to Figure 4, we see that in my second embodiment, I have substituted tackle 40, actuated by winch 41 on main frame 11, for tension member 30 to support the mast 27 at various inclinations (shown dotted) above and below the inclination of boom 12, thereby providing a decreased or increased digging component as desired. Excessive compression stresses in the mast, when it is dropped to a lower position to produce an increased digging component for lower positions of the dipper, are avoided by pivoting the mast on the main frame rather than high on the boom, thereby maintaining a substantial angle of incidence between tackle 40 and the mast 27.

Having now described and illustrated two forms of my invention, I wish it to be understood that my invention is not to be limited to the specific forms or arrangements of parts hereinbefore described, and shown.

I claim:

1. In an excavating machine the combination of: a base; an elevated structure thereon; a hoist winch; an upwardly inclined boom mounted at its foot on the base for free swivelling movement about the longitudinal axis of the boom; support means for the boom, extending from the elevated structure to approximately the upper end of the boom and swivelly connected to the boom for said swivelling movement of the boom; a mast mounted at its foot on the base and inclined upwardly therefrom with its upper end extending appreciably beyond the upper end of the boom; support means for the mast distinct from the boom support means and extending from the elevated structure to the upper end of the mast; a sheave carried by the mast approximately at its upper end; a dipper handle; a digging dipper carried

by the handle; support means connecting the dipper handle to the boom at approximately the upper end of the boom, said support means including a transverse horizontal shipper shaft located approximately at the upper end of the boom and a saddle block pivoted on said shipper shaft for swinging in a vertical plane, the handle being mounted in said saddle block for reciprocating movement with respect to the boom along the axis of said handle; means to reciprocate the handle assembly; and a hoist line, distinct from the boom support means and extending from a direct connection to the dipper and handle, over the sheave, to the winch.

2. An excavating means according to claim 1, 15 further characterized by the fact that the support means for the boom has a normally fixed length and that the mast is normally approximately parallel to the boom.

3. In an excavating machine the combination 20 of: a base; an elevated structure thereon; a hoist winch; a dipper handle; a digging dipper carried by the handle; support means supporting the dipper handle on the base for lateral swinging of the handle, for pivotal movement of the handle 25 in a vertical plane, and for reciprocation of the handle with respect to the handle support means along the axis of the handle; said handle support means including an upwardly inclined boom mounted at its foot on the base, and support 30 means for the boom extending from the elevated

5
16

structure to approximately the upper end of the boom; a mast mounted at its foot on the base and inclined upwardly therefrom with its upper end extending appreciably beyond the upper end of the boom; support means for the mast distinct from the boom support means and extending from the elevated structure to approximately the upper end of the mast; a sheave carried by the mast approximately at its upper end; means to reciprocate the handle; and a hoist line, distinct from the boom support means, extending from a direct connection to the dipper and handle assembly, over the sheave, to the winch.

TREVOR O. DAVIDSON.
